UNITED STATES PATENT OFFICE.

GUSTAV E. SCHELLMAN, OF NEW YORK, N. Y.

HAT-STRETCHER.

SPECIFICATION forming part of Letters Patent No. 389,014, dated September 4, 1888.

Application filed April 12, 1888. Serial No. 270,400. (No model.)

To all whom it may concern:

Be it known that I, GUSTAV E. SCHELLMAN, of the city, county, and State of New York, have invented a new and useful Improvement 5 in Hat-Stretchers, of which the following is a full, clear, and exact description.

This invention relates to hat-stretching rings or devices which are provided with independent auxiliary stretching attachments to make 10 the hat conform to special or peculiar shapes of the head at certain parts thereof; and the invention consists in certain novel constructions and combinations of parts, substantially as hereinafter described, and pointed out in 15 the claims.

Reference is to be had to the accompanying drawings, forming a part of this specification, in which similar letters of reference indicate corresponding parts in both the figures.

20 Figure 1 represents a view in perspective of a hat-stretcher embodying my invention; and Fig. 2, a perspective view of one side of the stretcher in part, as seen from its interior.

25 A A are the two main stretching sections, constituting the usual divided oval band or "ring," and adjustable toward or from each other in direction of the major axis of the oval figure by means of a right and left hand threaded screw, B, having an attached central hand-nut, b, and working at its opposite ends within boxes C C, secured to the interior of the end portions of the divided main stretching-sections A A, as usual in other hat-stretchers. Straps c c, secured at their one end to 30 the interior of the one section A on its opposite sides and passing through slotted projections d d upon the interior of the other section A on its opposite sides, serve to guide or 35 regulate said two sections during their movement in or out by the screw B.

40 Arranged upon the exterior of the sides of the divided band or band-sections A A, which are made of metal, are four movable wings, 45 D D, also made of metal, and of about the same depth or width as the main band. These wings, of which there are two to each section A, are coupled thereto by constructing them

with hook-shaped and notched inner ends, e, made to loosely clip and interlock with the 50 inner stepped and notched ends, f, of the section A to which they are applied; or they may be otherwise coupled to the main band-sections A, to work in a hinge-like manner from the inner end portions of said sections 55 A. Said wings D D are of a length to take in the sides and a portion of the outer ends of each main band-section A, and are curved in direction of their length to conform thereto, so that when shut down upon the sections A 60 A they will lie close thereto.

Pivoted to the inner face of each wing D, as at g, is a curved lever-catch, E, arranged to pass through a slot, h, in the sections A, and serving, when the wing is closed down on its 65 main section A, to lie up against the interior of said section and keep the wing closed, but which, when the wing is adjusted outward or thrown open, engages with any one of a series of notches or teeth, i, forming a fixed 70 rack on the side of either box C. Each wing D is thus made independently adjustable to any outward set required by the engagement of its lever-catch E with its rack i at different 75 points in the length of the latter. This forms a very simple and efficient combination, either for using the hat-stretcher, when the wings 80 D are closed, as an ordinary stretcher in direction of the major axis of the oval divided band A A, or, when either or any or all of the wings 85 D are independently set outward, for shaping the hat, on suitably turning the screw B, to conform to special abnormal configurations of the head or bumps or protuberances thereon, said wings being adjusted to any desired angle 85 for the purpose, and thereby making the hat conform to any shape required.

Having thus described my invention, what I 90 claim as new, and desire to secure by Letters Patent, is—

1. In a hat-stretcher, the combination, with the oval-shaped divided main band formed by independent sections A A, and a screw applied thereto adapted to adjust said sections in or out, of the independently-adjustable 95 outer curved wings, D, shaped to conform to

the exterior of said sections and in connection with the inner ends of said sections, substantially as specified.

2. The combination, with the adjustable main band-sections A A, their adjusting-screws B, and boxes C C, of the independently-adjustable curved wings D, in hinge-like connection with the inner ends of said sec-

tions, the lever-catches E, pivoted to said wings, and the fixed racks or notched portions to i, essentially as shown and described, and for the purpose herein set forth.

GUSTAV E. SCHELLMAN.
